Inventor:

Frederick A. Mason.

UNITED STATES PATENT OFFICE.

FREDERICK A. MASON, OF PROVIDENCE, RHODE ISLAND.

CONDIMENT-CONTAINER.

1,265,935.

Specification of Letters Patent. Patented May 14, 1918.

Application filed October 23, 1917. Serial No. 198,101.

To all whom it may concern:

Be it known that I, FREDERICK A. MASON, a citizen of the United States, and residing at 259 Washington St., Providence, R. I., have invented certain new and useful Improvements in Connection with and Appertaining to Condiment-Containers.

This invention relates to condiment containers of the type more particularly adapted for holding salt or the like, for table use, and the primary object of this invention is to provide a closure for the container, which will be practically air-tight, for the purpose of excluding moisture or other foreign matter therefrom.

It is found in practice in containers of this character, particularly in which salt is held, that moisture from the air, especially in moist climates or in the summer time, is absorbed by the contents causing it to cake and so prevent free delivery thereof from the holder.

By the use of my improved closure-member the moisture is effectively excluded, keeping the contents dry and always free to be readily discharged through the perforations in this closure.

With these and other objects in view, the invention consists of certain novel features of construction, as will be more fully described, and particularly pointed out in the appended claim.

In the accompanying drawings:

Figure 1—is a view of the container partly in section showing my improved closure connected thereto.

Fig. 2—is a top view of the closure-member with the stopper removed therefrom.

Referring to the drawings, 10 designates a condiment container which is preferably formed of glass having a neck portion 11 which is exteriorly threaded as at 12. This container may be made in any desired or convenient form and of any suitable material.

My invention relates essentially to the

particular form of closure for this container, wherein the same is sealed or formed air-tight, which closure comprises essentially a cap member 13 of metal or other suitable material, threaded as at 14, to engage the screw 12 on the neck of the container, the top 15 of the cap being perforated for the purpose of breaking up and sprinkling the contents upon food, when used as a shaker.

One of the essential features of my invention is the provision of a tubular neck portion 16 extending outwardly from the cap into which neck portion a cork 17 or other suitable stopper member may be forced to exclude all moisture and foreign matter from the contents of the container.

In some cases it is found that the cap-member is not absolutely air-tight when screwed onto the neck of the container. To obviate this difficulty I have provided a packing ring 18 of rubber or other suitable material, which is bound by the cap against the top edge of the container, thereby forming an air-tight closure, to exclude moisture from the container and maintain the contents thereof perfectly dry and in condition to be readily discharged through the perforations in the cap when the stopper is removed from the neck thereof.

The device is extremely simple, practical and inexpensive in construction, and by its use the usual annoyance in the use of a salt shaker in humid atmospheres, is obviated.

I claim:

A sealing closure for condiment container comprising a perforated cap formed of thin sheet material having its body threaded to engage the threaded neck of a container, a ring packing bottomed in said cap to form a tight joint between it and the neck of the container, an outwardly extending tubular neck portion on said cap, and a readily removable stopper fitting into said neck.

FREDERICK A. MASON.
